Primary Examiner — T. Chase Nelson*Assistant Examiner* — Eric Goodman(74) *Attorney, Agent, or Firm* — Richard L. Miller(57) **CLAIM**

The ornamental design for a collapsible portable hunting blind, as shown and described.

DESCRIPTION

FIG. 1 is a front, top, left side perspective view of a collapsible portable hunting blind showing my new design;

FIG. 2 is a rear, top, right side perspective view thereof;

FIG. 3 is a left side elevational view thereof;

FIG. 4 is a front elevational view thereof; and,

FIG. 5 is a rear elevational view thereof.

The broken line showing of the camouflage surface pattern is included for the purpose of illustrating environment and forms no part of the claimed design.
